UNITED STATES PATENT OFFICE

133,396

DESIGN FOR A SHOE

Isidore Busom, Port Washington, N. Y.

Application June 20, 1942, Serial No. 107,276

Term of patent 3½ years

To all whom it may concern:

Be it known that I, Isidore Busom, a citizen of the United States of America, residing in Port Washington, L. I., county of Nassau, and State of N. Y., have invented a new, original, and ornamental Design for a Shoe, of which the following is a specification, reference being had to the accompanying drawing, forming part thereof.

The figure on the drawing is a front perspective view of a shoe showing my new design.

The opposite side presents substantially the same appearance as the side shown.

I claim:

The ornamental design for a shoe, substantially as shown and described.

ISIDORE BUSOM.
